SPECTACLE FRAME OR THE LIKE

Ralph J. T. Bauer and Armand De Angelis, Southbridge, Mass., assignors to American Optical Company, Southbridge, Mass., a voluntary association of Massachusetts

Application February 12, 1953, Serial No. 23,577

Term of patent 14 years

(Cl. D57—1)

To all whom it may concern:

Be it known that Ralph J. T. Bauer and Armand De Angelis, citizens of the United States of America, residing at Southbridge, in the county of Worcester and State of Massachusetts, have invented a new, original, and ornamental Design for a Spectacle Frame or the like, of which the following is a specification, reference being made to the accompanying drawings, forming a part thereof.

Fig. 1 is a front elevational view of a spectacle frame, showing our new design;

Fig. 2 is a top plan view of the spectacle frame shown in Fig. 1 with the ends of the temples broken off; and

Fig. 3 is a side elevational view thereof.

The dominant features of our design reside in the portions shown in full lines in the drawing.

We claim:

The ornamental design for a spectacle frame or the like, substantially as shown and described.

RALPH J. T. BAUER.
ARMAND DE ANGELIS.
